United States Patent Office.

WILSON H. BERDAN, OF MOOREVILLE, MICHIGAN.

Letters Patent No. 103,833, dated June 7, 1870.

IMPROVEMENT IN MILL-BOLTS.

The Schedule referred to in these Letters Patent and making part of the same.

To all whom it may concern:

Be it known that I, WILSON H. BERDAN, of Mooreville, in the county of Washtenaw and in the State of Michigan, have invented certain new and useful Improvements in Mill-Bolts; and do hereby declare that the following is a full, clear, and exact description thereof, reference being had to the accompanying drawing and to the letters of reference marked thereon making a part of this specification.

The nature of my invention consists in the construction and arrangement of a flour-bolt, as will be hereinafter fully set forth.

In order to enable others skilled in the art to which my invention appertains to make and use the same, I will now proceed to describe its construction and operation, referring to the annexed drawing, in which—

Figure 1 is a transverse vertical section, and

Figure 2 is a longitudinal vertical section of my flour-bolt.

Figure 3 is an enlarged end view of one of the ribs.

A represents the central shaft of the "flour-bolt," from which radiate a number of series of arms, B B, to the outer ends of which the ribs C C are attached, all of said ribs running parallel with the axle or shaft A.

The ribs C C are three-cornered, the longest side being inside of the bolt, the cloth being secured to the two shortest sides, thus bringing a flat surface without corners inside of the bolt. This causes the flour to slide quietly along leaving the bran on top of the flour all the time.

The best flour-bolts are those which are as near round as possible, having no sharp corners in which

the flour will be caught. In most all the bolts now in use there are such sharp corners which carry the flour upward, letting it fall down again, turning it, and causing specks in the flour.

By having the flat ribs C C, there are no sharp corners, and the flour is caused to slide smoothly along without turning, leaving the bran on the top.

On the outside of the bolt are placed wooden hoops or bands, E E, which hold the ribs to their places. For each of these hoops or band I can dispense with one set or series of (six) arms inside of the bolt.

These arms B B continually carry more or less flour up with them, and letting it fall again, so that I consider it quite an object to lessen the number of these arms as much as possible. With three hoops or bands on the outside, there will be eighteen arms less on the inside.

Having thus fully described my invention, What I claim as new, and desire to secure by Letters Patent, is—

1. A rib for a flour-bolt, flat upon the inside, reaching the cloth with each edge, and beveled on the outside, so as to let the cloth bear directly upon the edge, substantially as herein set forth.

2. The combination, in a mill-bolt, of the triangular ribs C C, with or without the arms B B, and the exterior hoops E, all substantially as set forth.

In testimony that I claim the foregoing, I have hereunto set my hand this day of , 1870.

W. H. BERDAN.
